(57) **CLAIM**

The ornamental design for dental model base with a plurality of indexing pins, as shown and described.

DESCRIPTION

FIG. 1 is a front perspective view of a dental model base with a plurality of indexing pins showing my new design;

FIG. 2 is a rear perspective view thereof.

FIG. 3 is a top view thereof.

FIG. 4 is a left side view thereof.

FIG. 5 is a right side view thereof.

FIG. 6 is a rear view thereof.

FIG. 7 is a front view thereof; and,

FIG. 8 is a rear perspective view thereof with a partial dental mold mounted thereto.

The portions of the article in broken lines are shown for illustrative purposes only and form no part of the claimed design.

1 Claim, 5 Drawing Sheets
